CLAIM

The ornamental design for a transportable storage box, as shown and described.

DESCRIPTION

FIG. 1 is top plan elevational view of a transportable storage box illustrating a new design;

FIG. 2 is a front elevational view thereof;

FIG. 3 is a bottom view thereof;

FIG. 4 is a left elevational view thereof, the right elevational view being a mirror image thereof;

FIG. 5 is rear elevational view thereof; and,

FIG. 6 is an isometric view thereof when the transportable storage box is opened to store matter.

The broken lines are for environmental purposes only and form no part of the claimed design.
